We claim the ornamental design for a threaded coral reef nut, as shown and described.

DESCRIPTION

FIG. 1 is a top, front, right isometric view of the threaded coral reef nut showing our new design;

FIG. 2 is a bottom, rear, left isometric view thereof;

FIG. 3 is a front view thereof;

FIG. 4 is a right side view thereof;

FIG. 5 is a rear view thereof;

FIG. 6 is a left side view thereof;

FIG. 7 is a top view thereof;

FIG. 8 is a bottom view thereof;

FIG. 9 is top, front, right isometric view of an assembly of the threaded coral reef nut shown in FIGS. 1-8 with a coral reef nail;

FIG. 10 is a bottom, rear, left isometric view of FIG. 9;

FIG. 11 is a front view thereof;

FIG. 12 is a right side view thereof;

FIG. 13 is a rear view thereof;

FIG. 14 is a left side view thereof;

FIG. 15 is a top view thereof; and,

FIG. 16 is a bottom view thereof.

The broken lines are included for the purpose of illustrating environmental structure and form no part of the claimed design.

The shade lines in the Figures show contour and not surface ornamentation.
